TOY STRUCTURAL ELEMENT AND JOINT
MADE THEREFROM

Joseph E. Grant, Beverly Hills, Calif.

Application March 14, 1941, Serial No. 383,271

16 Claims. (Cl. 46—16)

This invention relates to toy structural elements and to joints made therefrom.

The general object of the invention is to provide an improved toy or other structural member which may be made of fibrous or other material such as light weight cardboard and which can be readily completed and easily erected.

A more specific object of the invention is to provide a toy structural building element.

An additional object of the invention is to provide a structural element including a base with sides thereon and with a rib projecting therefrom.

Another object of the invention is to provide a structural member including a built-up girder made of novel shape.

A further object of the invention is to provide a novel joint for structural elements.

An additional object of my invention is to provide a novel wheel.

Other objects and advantages of the invention will be apparent from the following description taken in connection with the accompanying drawings, wherein:

Fig. 1 is a side elevation of a bridge embodying the features of my invention.

Fig. 1A is a perspective view of the element embodying the features of my invention.

Fig. 1B is an end view of the element.

Fig. 1C is a fragmentary perspective view of a girder.

Fig. 2 is a section taken on line 2—2 of Fig. 1, and looking in the direction of the arrow.

Fig. 2A is a fragmentary section taken on line 2A—2A of Fig. 2.

Fig. 2B is a fragmentary section taken on line 2B—2B of Fig. 2.

Fig. 3 is a section taken on line 3—3 of Fig. 1 and looking in the direction of the arrow.

Fig. 4 is a section taken on line 4—4 of Fig. 1.

Fig. 5 is a section taken on line 5—5 of Fig. 1.

Fig. 6 is a section taken on line 6—6 of Fig. 5.

Fig. 16 is an enlarged fragmentary section taken on line 16—16 of Fig. 2.

Fig. 17 is an enlarged fragmentary side elevation partly in section of the lower arcuate portion of the bridge shown in Fig. 1.

Fig. 18 is a section taken on line 18—18 of Fig. 17.

Fig. 19 is an enlarged fragmentary section taken on line 19—19 of Fig. 3.

Fig. 20 is a perspective view of portions of the elements shown in Fig. 19 in the process of making up the element.

Fig. 21 is a side elevation showing a modified girder.

Fig. 22 is an end view of the modified girder.

Fig. 23 is an enlarged section taken on line 23—23, Fig. 2.

Fig. 24 is a section taken on line 24—24 of Fig. 23.

Fig. 25 is a fragmentary side elevation of a length of structural element having an integral loop formed therein.

Fig. 26 is a fragmentary side elevation showing a right angled joint for two elements wherein the rib portion is to the outside of the angle.

Fig. 27 is an enlarged fragmentary top plan view of the device shown in Fig. 26.

Figs. 28, 29 and 30 show a means of joining aligned horizontal and vertical structural elements.

Fig. 31 is a section taken on line 31—31 of Fig. 30.

Fig. 32 is a plan view of a gummed binder strip.

Fig. 33 shows a joint means for offset horizontal and vertical structural elements.

Fig. 34 is a side elevation of a wheel formed of lengths of my structural element, and

Fig. 35 is an enlarged fragmentary section taken on line 35—35 of Fig. 34.

Referring to the drawings by reference characters, I have shown my invention as embodied in a structural element which is indicated generally at 10.

As shown, the structural element is made from a strip of material and includes a base 11, having a side portion 12 bent to overlap a portion of the base. From the side portion, a flap 13 extends upwardly and a second flap 14 integral with the first flap extends downwardly and is integral with a side 15 which overlaps the base. The sides 12 and 15 are glued to the base and a

coating of glue 16 is arranged on the interior of the flaps 13 and 14 and on the inner exposed portion of the base 11. This glue is of the type which is rendered tacky by moistening and its use will be hereinafter explained. The flaps 13 and 14 together form a rib which serves to stiffen and strengthen the base as will be readily understood. It will be noted that as shown in Fig. 1B of the drawings the width across the bottom of the rib is less than one third of the width of the base and that the height of the rib is greater than one half the width of the base, also the height of the rib is more than twice the width across the bottom of the rib.

In the use of my invention I may employ the elements 10 in various ways, as for instance in Fig. 1, I have shown a plurality of the elements as built into a bridge indicated at B.

The bridge shown consists of two sides 17 and 18 which are identical in construction. The ends of each side indicated at 19 and 20 are complementary from the center line of the bridge 21 (Fig. 1) outwardly towards each end and therefore to shorten the specification the construction of only one-half of one side will be given in detail. The end 19 includes an element 22 like that shown in Fig. 1A. The element 22 includes a portion 23 of which the base 23' (see Figs. 1 and 16) is directed horizontally and the rib 24 in this portion is directed downwardly. The element 22 has the peak of the rib cut away as at 25 (Fig. 16) and the base 23' is bent as at 26 to form a vertical portion 27 and the rib 24 is again cut away as at 28 and the base of the element is again bent to form a horizontal portion 29 which may engage any suitable support or abutment.

The glue on the inner face of the ribs is moistened and engages the overlapping portion of the ribs to cause the parts to adhere together thus securing the parts in the position shown in Figs. 1 and 16. The upper end of the element 22 is connected by a joint 30 as shown in Figs. 5 and 6 to a second element 31. This joint is effected by cutting the base 31' of the element 30 away from the adjacent portion of the rib thus forming a slot 32 (Fig. 5). The element 22 is then telescoped into the spread-apart ends of the element 31 and the adjacent portions of the ribs and bases are glued together.

The portion 28 of the element 22 is connected to an arcuate member 33. This arcuate member as shown in Figs. 17 and 18, consists of a pair of elements 34 and 35. These elements are alternately slotted as at 36 and 37 along the rib portions thereof thus allowing the ribs to take an arcuate form while the bases of the elements 34 and 35 remain uncut.

In this construction the bottom portion of the base of the element 34 remains undisturbed but as shown in Fig. 18, the bottom portion of the element 35 is removed so that only the sides 38 and 39 remain and these are secured to the tops of the base of the element 34 in the position shown in Fig. 18. The adjoining overlapping portions of the ribs are glued together with the notches 36' and 37', formed by the slits 36 and 37 out of registry as shown in Fig. 17, so that the arcuate member 33 has a continuous rib made up of two severed and connected ribs.

The lower end of the arcuate member 33 has the rib 40 thereof inserted in a slit 41 which slit extends along the crest of the rib of the portion 28 as shown in Fig. 16. The end 42 of the arcuate member 33 is connected by a joint 41 which may

be like the joint 30 shown in Figs. 5 and 6 to a horizontal element 43.

The elements 30 and 43 have their ribs directed towards each other and the tips of the ribs are spaced apart as shown in the drawings. The ribs as shown in Fig. 4 are connected by plates 44 and 45. The plates 44 and 45 are similar and only the plate 44 will be described. This plate 44 includes an upper panel portion 46 engaging the rib on the element 30 and a lower panel portion 47 engaging the rib on the element 43. The portions 46 and 47 are integral with an intermediate portion 48 and the intermediate portion 48 is connected to the intermediate portion 49 on the plate 45. The plate 44 as well as the plate 45 is provided with spaced outwardly directed reinforcing ribs 50. Each rib includes flaring panel portions 51 connected to wedge-shaped portion 52 at the middle of the rib as shown in Fig. 7 of the drawings. The portions 46, 47 and 51 are preferably plane and are defined by crease lines 46', 47' and 51'. The portions 46, 47 and 48 may be partially cut away to form a grill as shown at 53 in Fig. 1 if desired.

By referring to Fig. 1 it will be noted that there is an element 22 at each end of the bridge and that these elements are connected by the upper element 31 of the girder.

On the outer end of each upper portion of the element 22 I arrange an upwardly convergent strut element 60 which is shown in detail in Fig. 16. The strut 60 is formed by transversely cutting through the rib of a structural member and longitudinally slitting the ridge at one side thereof and then bending the ribs towards each other. The rib of one section is inserted through the slit of the other section and glued thereto as at 61. The rib 61 of the element is shown as cut away along the line 62 thus providing a lip 63 which is glued to the outer surface of the vertical portion 27 of the element 22 and the horizontal base portion of this element 22 is slotted as at 64 to receive the rib 61 of the member 60. This portion is secured to the inner surface of the rib on the portion 23.

Intermediate the ends of the girder I provide an upwardly converging strut 70 as shown in Figs. 1 and 14. The strut 70 like the strut 60 is formed by transversely cutting through the rib of a structural member and longitudinally slitting the rib at one side thereof and then bending the ribs towards each other. The rib of one section is inserted through the slit of the other section and glued thereto as indicated at 71. The ribs of the strut 70 at the bottom thereof are cut away as shown in Fig. 14 leaving a free base portion 72 of the element 70 which is secured to the base of the element 31. The rib ends 74 on the struts 70 are arranged in slots 76 in the base of the element 31 and these portions 74 are secured to the adjacent walls of the rib on the element 31.

The base portion of the strut 60 adjacent the inner end thereof is severed from the rib portion to form a lip 75 which is bent upwardly and glued to the adjacent base of the strut 70. The adjacent rib portion 61 of the strut 60 like the rib of the strut 70 extends through a slot 77 in the base of the element 31 and this portion is glued to the adjacent walls of the rib of the element 31.

At each of the ends 19 and 20 an upper transverse girder 80 is provided. As shown in Fig. 19 the girder 80 is formed of a pair of parallel structural members 81 and 82 having adjacent portions of their bases connected by a strip of material 83 glued thereto (see Fig. 20). The strip

83 is then bent until the bases of the structural members are at right angles with the peaks of the ribs abutting.

A strip of material 84 is then placed over the rib peaks and glued to each of the ribs. At each end the rib portion of the member 81 is cut away to fit against the ribs of the members 22 leaving lips 85 which are glued to the tops of the horizontal members 23 and lips 85' which are glued to the ribs of the members 23. At each end the rib portion of the member 82 is cut away to fit against the ribs of the members 22 leaving lips 86 which are glued to vertical members 27.

The ends 19 and 20 are each further reinforced by diagonally extending cross members 86' and 87 each of which is formed from a length of structural member. At the lower ends the ribs of the members 86' and 87 are severed from their bases and split to form lips 88 which are glued to the ribs of the adjacent members 27. The bases of the members 86' and 87 at the lower ends thereof are glued to the outer faces of the vertical members 27.

At their upper ends the ribs of the members 86' and 87 are severed from their bases and split to form lips 89 which are glued to the ribs of the adjoining members 27 and 80. The bases of the members 86' and 87 at the upper ends thereof are glued over the lips 72 of the strut members 70.

Furthermore each of the ends 19 and 20 includes a lower transverse member 90 which is formed of a length of structural member turned sidewise and at each end has a portion of the rib cut away to provide a lip 91 which is glued to the adjacent vertical member 27.

The end struts 60 are connected by an arcuate member 100 (Fig. 1) which is formed of a length of structural member 10 the rib 101 of which has wedge-shaped portions cut therefrom as indicated at 102. Over the rib 101 of the member 100 another structural member 103 having the base removed therefrom is positioned and glued thereto. The member 103 like the member 101 has wedge-shaped portions cut therefrom as indicated at 104. The cuts 104 of the member 103 are positioned intermediate the cuts 102 of the member 101.

At each end the rib portion of the member 101 is cut away leaving lips 105 which are glued to the bases of the end strut 60. Opposite the lips 105 the bases of the struts 60 are slit to receive the ends of the ribs of the member 100 as indicated at 106.

The strut member 70 at the peak thereof is slit to receive the rib of the member 100 (see Figs. 10 and 11).

Adjacent each of the struts 70 and between the struts 70 the bridge includes transverse members 108 (see Figs. 2 and 11). The rib portions 109 (Figs. 11 and 12) of the center member 108 are cut away to fit over the vertical rib 52 of the girder plate 44 leaving lips 110 which are glued to the girder plate and leaving a base lip 112 which is glued over the element 31.

Similarly the ribs of the end transverse members 108 are severed from the base leaving lips 113 which are glued to the elements 31. The severed portions of the ribs are slit to form lips 113' which are glued to the girder plate 44 (see Fig. 2A).

Extending from the peak of the strut 70 to the element 31 I provide a tension member 115 which adjacent the top thereof at 116 is glued to the rib of the strut 70 and at the lower end is glued 75

to the base of the central transverse member 108 and has a hold down strip 117 glued thereover and to the base of the central transverse member 108.

- 5 Adjacent the struts 60 the arcuate members 100 are connected by transverse members 120 (Fig. 2) each of which is formed from a structural member 10 having the rib portion 121 thereof severed from the base leaving a lip 122 which is glued to the base of the arcuate member 100. The severed portions of the ribs 121 are slit to form lips 123 which are glued to the rib of the arcuate member 100 (see Fig. 2B).

- Intermediate the length of the arcuate member 100 a transverse member 125 is provided. The member 125 is formed from two lengths of the structural element 10 an upper section 126 and a lower section 127 having their base portions glued together. The rib 128 at each end of the lower section 127 is cut away to fit against the strut 70 leaving a lip 129 which is glued to the base portion of the arcuate member 100.
- 15 20 For appearance the ends of the rib 130 of the upper section 126 are beveled as at 131 (see Fig. 2).

- 25 In Figs. 21 and 22 I have indicated a plate element generally at 135 which may be used to form a floor for the bridge B. The element 135 is formed of a sheet of flat material which forms 30 a base 136 which is bent at spaced distances to form V-shaped transverse ribs 137. Adjacent each side of the base 136 I provide reinforcing members 138. The members 138 are each formed from a length of the structural element 10 and 35 have the bases 139 thereof glued to the face of the base 136 opposite the ribs 137.

- In Figs. 23 and 24 I have shown a means for reinforcing cross bracing such as the cross bracing 86 and 87 shown in Fig. 2. The reinforcing member is indicated generally at 140 and is formed from a length of the structural member 10. The rib of the member 140 is severed along the peak thereof thereby forming flaps 141 from the sides of the rib which are glued to the sides 40 45 of the rib of the cross member 87 and the base 142 of the member 140 is glued to the peak of the ribs of both the cross members 86 and 87.

- In Fig. 25 I have shown a means for forming an integral loop intermediate the length of a structural element 142 which is formed from a length of the structural element 10. As shown the rib 143 of the element 142 is transversely severed leaving the base 144 intact. In line with the rib severing the base 144 is crimped and bent 50 55 downwardly to form a V-shaped loop 145. Above the loop 145 one portion of the rib 143 is positioned over the adjacent portion as at 146 and glued thereto.

- In Figs. 26 and 27 I show a means for forming a right angle joint between two elements similar to the element 10 when the ribs are positioned on the outside of the angle. In Fig. 26 I show a vertical member 148 and a horizontal member 149 each of which are formed from a length of the structural element 10. As shown the base 150 of the vertical member 148 is severed from the rib portion 151 adjacent the end of the member and bent at right angles to form a lip 152.

- Adjacent the end the base 153 of the horizontal member 149 is severed from the rib portion 154 for a predetermined distance and is then severed from the remaining portion of the base as shown at 155. Glue is then placed on the inside of both ribs 151 and 154 adjacent the joining ends and then the end of the rib 151 is positioned

over the end of the rib 154 and the two ribs pressed together as shown in Fig. 27. The lip 152 of the vertical member 148 is then glued to the under face of the base 153 of the member 149.

In Figs. 28 to 32 I show a means for connecting structural members similar to the structural element 10 by means of gummed strips of flexible material such as paper.

In Figs. 28 to 31 I have shown a horizontal member 158 and a vertical member 159 both of which are formed from a length of the structural element 10 and in Fig. 32 I have indicated a gummed paper binder strip generally at 160. As shown the binder strip 160 is formed from a narrow length of paper 161 which is gummed on one side as indicated at 162. The face of the paper 161 opposite the gummed side has a plurality of spaced, transversely extending cut lines indicated thereon such as by dotted lines 163 to form a plurality of binder tabs 164. Intermediate the width thereof the paper 161 has a plurality of spaced slots 165 therein which extend from one cut line 163 halfway to the next cut line.

In use the binder strip 160 is transversely severed at the cut lines 163 to form individual binder tabs 164 each of which includes a body portion 166 having two integral lips 167 extending therefrom.

To secure the members 158 and 159 together a wedge-shaped notch 170 is cut in the end of the base 171 of the member 159 as shown in Fig. 28 and the rib 172 thereof is severed along the ridge as at 173 in Fig. 30. The rib 174 of the member 158 is positioned in the V-shaped notch 170 and the sides of the rib 172 are positioned over the sides of the rib 174 of the member 158. The gummed surface of one of the tabs 164 is then moistened and the body portion 166 thereof is placed over the peak of the rib 174 and folded downwards to engage the side of the rib.

The lips 167 of the tab are then placed over the sides of the vertical rib 172. Another of the tabs 164 is then moistened and the body portion 166 thereof is placed over the peak of the rib 174 and folded down to engage the sides of the rib on the side of the vertical member 159 opposite the first tab. The lips 167 of the second tab are then bent at right angles and placed against the base 171 of the vertical member and around the sides of the base as clearly shown in Fig. 31.

In Fig. 33 I have shown means for securing a horizontal structural member 175 and vertical structural member 176 together when the assembly is such that the vertical rib extends towards the horizontal rib. A portion of the base 176 of the vertical member 176 is cut away adjacent the end leaving a portion of the base 176 extending which forms a lip 177. The rib 176 is then longitudinally slit as at 178 intermediate the peak thereof and the base 176. The severed peak portion is then bent outward and flattened to form a lip 179.

The end of the rib 176 of the vertical member 176 is then placed on the upper surface of the base 175 of the member 175 at one side of the rib 176 thereof with the lip 179 extending over the horizontal rib 175 and glued to the side thereof. The lip 177 of the vertical member 176 is then bent at right angles below the horizontal member 175 and glued to the under face of the base 175 of the horizontal member.

In Figs. 34 and 35 I show a wheel 180 which is formed from a plurality of lengths of the struc-

tural member 10. As shown the wheel 180 includes a rim portion 181, a hub portion 182 and spokes 183.

The rim 181 includes an outer member 184 and an inner member 185.

The inner member 185 is made of a length of the structural element 10 with the base omitted and includes only side portions 186 and a rib 187 which is transversely severed at equally spaced distances. Adjacent every other cut the peak of the rib is longitudinally slit a predetermined distance.

The member 185 is formed circular by placing it in a circular form (not shown) and then bending it therearound after which a length of cord 188 is placed within the rib 187 and securely tied. As the member 185 is bent around the form the severed ends of one portion of rib 187 are positioned within the slit ends of the adjacent rib portion and glued thereto as at 189.

The outer member 184 is formed from a flat piece of material glued to the sides 186 of the inner member. At the juncture with the rim one portion of the rib is slit adjacent the base thereof as at 190 to receive the flange portion of the adjacent portion, the rib portion of which is positioned in the slit rib portion and all the overlapping portions of the rim are glued together.

The hub portion 182 includes two members 190 and 191 each of which is formed of a length of the structural element 10. The hub 182 is formed by gluing the bases 192 of the members 190 and 191 together with the ribs 193 of the members positioned at right angles to each other. Intermediate the length of the ribs 193 an aperture 194 is formed through the peaks of the two ribs 193 to receive an axle.

The spokes 183 are each formed from a length of the structural material 10. Adjacent the outer end thereof the base 195 and the rib 196 of each of the spokes is cut to fit over the rib 187 of the rim and is glued thereto. Likewise adjacent the inner end thereof the base 195 and the rib 196 of each of the spokes is cut to fit over the hub member 182.

Having thus described my invention, I claim:

1. As a new article of manufacture, a structural girder, said girder comprising a pair of structural elements, each element comprising a base and an upper portion, said upper portion including side portions secured to the adjacent portions of the base, and an upwardly extending hollow rib integral with the inner edge of the side portions, said elements being aligned with the ribs having their tips adjacent and a plate member secured to each side of the ribs and connecting the same, said plate members having their intermediate portions connected together.

2. As a new article of manufacture, a toy structural girder, said girder comprising a pair of structural elements, each element comprising a running strip including a base and an upper portion, said upper portion including side portions secured to the adjacent portions of the base and an upwardly extending rib integral with the inner edges of the side portions, said elements being aligned with the ribs having their tips adjacent and a plate member secured to each side of the ribs and connecting the same, said plate members each having integral transverse ribs disposed in planes perpendicular to the plane of the element rib members.

3. As an article of manufacture, a girder comprising a pair of elements, each element includ-

ing a base having an upwardly extending hollow rib thereon, said elements being aligned with the ribs being directed towards each other, a member connecting the ribs on each side thereof, the portions of said connecting members at each end of the girder being flared outwardly and an end member on each end of the girder, said end members each including an element having a base with a hollow rib projecting therefrom, said last mentioned hollow ribs being fitted between the flaring end portions of the connecting members and secured thereto.

4. In a building member, a pair of elements each including side portions having a hollow rib projecting therefrom, said ribs each including cut away portions and the elements being assembled with the ribs telescoped and with the side portions in engagement and with the cut away portions out of alignment, said side portions being bent into arcuate form and the side portions and the ribs of the two elements being connected together.

5. In a building member, a pair of elements each including side portions having a hollow rib projecting therefrom, said ribs each including cut away portions and the elements being assembled with the ribs telescoped and with the side portions in engagement and with the cut away portions out of alignment, said side portions being bent into arcuate form and the side portions and the ribs of the two elements being connected together, and a base secured to the outer side portions.

6. In a structural joint, a plurality of elements, each of said elements including a base having a hollow rib projecting therefrom, said elements being three in number, the first element having a pair of spaced slots in the base thereof and the second and third elements having the ends of their ribs inserted in the slots, the bases of the second and third elements extending beyond the ribs at one end thereof, the extending portion of the second element being secured to the base of the first element and the extending portion of the third element being secured to the base of the second element.

7. In a structural joint, a pair of structural elements each including a base having a hollow rib projecting therefrom, one of said elements having a slot in the base thereof aligned with the rib thereon and the other element having the end of its rib inserted through the slot, said other element including a portion of the base projecting beyond the rib and means to hold the parts in place.

8. In a building construction, a pair of elements each including side portions having a hollow rib projecting therefrom, said ribs being notched at intervals and the elements being assembled with the ribs and side portions in engagement and with the bases curved and with the notches on one rib staggered with respect to the notches on the other rib and means to hold the parts assembled.

9. In a building construction, a pair of elements each comprising a base having a hollow rib thereon, said elements being arranged with the bases adjacent and at right angles and with the tips of the ribs engaging, means engaging the bases and extending across the joint therebetween to connect the bases and means engaging the outer surfaces of the ribs to hold the ribs together.

10. In a building construction, a pair of elements each having a hollow rib thereon and projecting therefrom, said bases being arranged coplanar and with the edges in abutting relation and a connecting strip engaging the upper surfaces of the bases between the ribs and having its edges engaging the ribs.

10. In a construction member, a base having spaced transverse ribs thereon and a reinforcing member extending along each side of the base, each of said reinforcing members comprising an element having a base and having a hollow up-standing rib thereon.

15. In a structural element joint, a pair of elements each including a base having a hollow rib projecting therefrom, one of said ribs being transversely cut and partially severed at the base on each side to form a notch, the other element being inserted in the notch and a third element having a base and a hollow rib thereon with the rib of the third element severed at its peak to provide two flaps, said flaps being notched and engaging the rib on said first element.

20. In a structural element, a base having a hollow rib extending therefrom, said base being severed from said rib for a predetermined distance, the severed rib portions being telescoped and secured together and the base portion adjacent the severed portion being bent to form a substantially wedge-shaped loop.

25. In a structural joint, a pair of elements, each of said elements including a base having a hollow rib extending therefrom, one of said elements having the base removed from a portion thereof to form a projecting rib at one end thereof, the other element being severed inwardly from the end at the juncture of the rib and the base to form a base flap, the base flap being bent to engage the rib on the first element and the projecting rib on the first element being inserted within the rib of the second element and means to hold the parts together.

30. As a new article of manufacture a toy structure girder, said girder including a pair of structural elements each element including a base having an upwardly extending hollow rib thereon, said rib comprising inclined, plane sides of equal length, said elements being aligned with the ribs directed towards each other, and a plate connecting the ribs on each side thereof, each plate including planar upper and lower panels directly engaging and secured to the inclined side of the adjacent rib, each plate having intermediate portions between the upper and lower panels, the intermediate portions being secured together.

35. As a new article of manufacture a toy structure girder, said girder including a pair of structural elements each element including a base having an upwardly extending hollow rib thereon, said rib comprising plane sides, said elements being aligned with the ribs directed towards each other, a plate connecting the ribs on each side thereof, each plate including planar upper and lower panels directly engaging and secured to the entire face of the adjacent rib side, said plates including outwardly flared portions, the plates at the ends of said outwardly flared portion having outwardly directed reinforcing ribs thereon.

JOSEPH E. GRANT.
